FIG. I

FIG. 2

FIG. 3

FIG. 4

INVENTOR

GEORGE R. ERICSON

BY J. H. Gibbs

ATTORNEY

UNITED STATES PATENT OFFICE

GEORGE R. ERICSON, OF ST. LOUIS, MISSOURI, ASSIGNOR TO CARTER CARBURETOR CORPORATION, OF ST. LOUIS, MISSOURI, A CORPORATION OF DELAWARE

CARBURETOR

Application filed April 24, 1930. Serial No. 446,899.

It will be understood that the invention is susceptible of many modifications, and, accordingly, I do not wish to be limited in my protection, except as set forth in the accompanying claims.

This invention relates to carburetors and more particularly to thermostatic controlling devices for carburetors. This application is a continuation in part of my application 10 #358,700 filed April 27th, 1929 which has resulted in Patent #1,872,708 granted August 23rd, 1932. It is an object of the invention to provide a simple and easily manufactured thermostatic controlling device for 15 varying the mixture ratio of fuel and air with the temperature.

It is a further object of the invention to produce a device of the above described character which will remain constant over a long 20 period of operation.

It is a further object of this invention to provide a thermostatic controlling device of the above described character in which the thermally operated element is heat treated 25 to eliminate strains in the metal and to provide a thermal element of such construction and arrangement as to permit the heat treatment of the element without distortion caused by the ends being forcibly brought 30 together during the heat treatment. The invention will be better understood upon reference to the accompanying drawing in which corresponding reference numerals represent corresponding parts throughout.

35 Referring to the drawing:

Figure 1 shows a vertical, sectional view of a carburetor embodying this invention.

Figure 2 shows an end view of a thermostatic control element of a carburetor according 40 to this invention.

Figure 3 shows a longitudinal sectional view of the parts shown in Figure 2.

Figure 4 shows an end view of the device shown in Figures 2 and 3 taken from the end 45 opposite to that shown in Figure 2.

The reference numeral 1 indicates a main body casting having an air horn or air inlet 2 therein. This air horn leads into an air chamber 3 which discharges through a venturi 4 formed in a second body member 5

which is attached to the first body member by suitable screws 6. The body member 5 is provided with a flange 7 by means of which it is attached to the inlet manifold of an internal combustion engine in the usual manner.

A throttle valve 8 mounted on a suitable shaft 9 is provided for controlling the outlet of the carburetor. The body member 1 is provided with a downward extension 10 surrounded by an annular seat 11, a cup-shaped bowl 12 is seated at its rim on the annular seat 11 and retained in position by a nut 13 which is threaded into the lower end of the extension 10.

Fuel is supplied to the bowl by any suitable means, such as an engine driven pump or a vacuum tank, and it is maintained in the bowl at substantially the level A—A by a conventional float mechanism 14. The inlet 70 connection and the float valve are not shown, these being so well known in the art that no further description is necessary.

A standpipe 15 is threaded into the lower portion of the air chamber as shown. Ports 75 16 are provided in the lower portion of the standpipe to receive air from the air chamber 3. A restricted throat 17 is formed in the standpipe above the entrance of the air inlet for the purpose of increasing the air 80 speed at that point to insure thorough vaporization of the fuel. An air bleed 18 is drilled in the lower portion of the standpipe and communicates with the well 19 formed in the extension 10 of the body member 1. 85 The well 19 is provided with screw threads 20 at its lower portion to receive the corresponding threads of the nut 13 and also to receive the threads of a nozzle 21 which is mounted concentrically with the well 19 90 extending from the lower portion of this well to the restricted portion 17 of the standpipe.

Accelerating holes 22 are provided for the nozzle and form a communication between the well 19 and the interior of the nozzle. Fuel is supplied to the well 19 and to the interior of the nozzle through suitable passages 22 and 23, respectively, which form 100 communication between the well and nozzle

and the space between the nozzle and the end of the nut 13, as indicated at 24.

A cross connection 25 supplies fuel to the lower end of the idling tube 26 and the fuel enters this tube through the small port 27, as shown. Conventional air bleeds 28 are provided in the idle tube above the fuel level, and the upper end of the tube is connected to a bore 28 in the body member 5. From this bore the fuel passes to an outlet port 29 in the side of the outlet passageway 30 of the carburetor. This port is formed at the the point where the throttle valve closes against the side of the passageway and when the throttle is slightly open, as it is when adjusted for proper idling, at least a portion of the port 29 is in communication with the mixing conduit at a point posterior to the throttle. In this manner a suction connection from a point posterior to the throttle is provided for admitting the idling fuel and for affecting the valve 42. When the engine is operating under its own power but at low speeds, for instance, with the throttle one-eighth open, the port 29 would be fully exposed to the suction above the throttle and that suction will be very high, perhaps corresponding to 7 or 8 pounds per square inch. Excellent vaporization of the gasoline is accordingly obtained, and it is therefore desirable to lean out the mixture to a certain extent. The suction connection comprising port 29, passages 28, 33, and 36 transmit the suction from above the throttle to the valve 42 causing it to close or partly close, and thereby lean out the mixture.

A transverse threaded bore 31 is formed in the extension 10 near the lower end of the carburetor and a body member 32 is threaded into this bore. Jet nozzle 32 comprises a large passageway 33 calibrated to meter the maximum quantity of fuel which it is desired to pass through the carburetor under low temperature conditions opening into a threaded bore 34 which receives the screw threaded ends of a second body member 35 having a longitudinal bore 36 of comparatively large diameter so that it does not form a restriction or calibration, and a small calibrated longitudinal bore 37 of considerably smaller diameter than the bore 36, a transverse bore 38 of larger diameter than the bore 37 is drilled in the body member 35 and provides the main communication between the bore 36 and the fuel in the bowl.

A bracket 39 having a perforation 40 is attached to the two body members by screwing them together, the perforation 40 surrounding the threaded end of the body member 35. The bracket is bent into a U shape at the end opposite the perforation 40 to provide a parallel short leg 41 to which may be attached the thermally operated controlling member 42. This control member is formed of a straight flat piece of the usual bi-metallic

thermostatic material, the more expansible metal being placed on the outside, and the less expansible metal being placed next to the end of the body member 35. The member 42 is held in place by any suitable means, such as a rivet 43. It will be understood that the member 35 may be inserted or withdrawn from the U-shaped bracket by swinging the member 42 on the pivot 43. When the member 42 is swung aside the member 35 may also be readily engaged by a wrench.

The passageway 38 is so calibrated that when the temperature is reasonably high, say, above 70 degrees Fahrenheit, in the fuel bowl of the carburetor, the combined resistance offered by the passageways 22, 23, and 38 regulate the flow of fuel to give a proper mixture for operating under high temperature conditions. It will be understood that the control member 42 moves to the left of the Figure 3 and closes when the temperature is in excess of approximately 70 degrees Fahrenheit, thereby closing the opening 37 and causing all the fuel for the carburetor to flow through the passageway 38. When the temperature falls below 70 degrees Fahrenheit in the fuel bowl, the member 42 moves to the right, opening the passageway 37, thereby enriching the fuel mixture by the capacity of the passage 37 which is approximately one-eighth of that of the passage 38. The fuel is then metered at the passage 33 and at the passages 22 and 23.

A feature of this invention is that the thermostatic metal is made comparatively short, but very thin, and flexible by mechanical force as well as by changes in temperature, and this has a very important object in this invention, in addition to securing the great cheapness and simplicity of construction which are also obtainable with this device.

In cold weather, when the automobile to which the carburetor is attached, is operated continuously at low speed, the fuel in the carburetor bowl will reach a temperature of approximately 70 degrees or more without very great delay; for instance, when the outside temperature is zero, the carburetor bowl will probably attain a temperature of 70 degrees within about three to five miles, but if the car is driven at high speed, for instance, in excess of 40 miles an hour, the rate of fuel flowing into the bowl is so rapid that the temperature existing in the bowl is likely to approach that existing in the fuel tank and not that of the engine. The fuel tank is ordinarily mounted at the rear end of the car and is very likely to be cold, and the rate of heat conduction down through the body of the carburetor being substantially constant, a rapid lowering of the temperature in the bowl is experienced, with the result that one would expect the thermostat to open up and give an undesirably rich mixture while driv-

ing the car at high speed in cold weather. This difficulty is overcome in my device by the following construction:

The thermally controlled element 42 is made very thin, say, in the order of .017 of an inch in total thickness of the two metals, and the length and width are so selected with respect to the suction of the carburetor that the suction at the end of the bore 37 at speeds above 40 miles an hour will bend the member 42 into contact with the face of the member 35, closing the bore 37. By reason of the fact that at speeds of 40 miles an hour or more, the fuel is thoroughly vaporized by the comparatively high air speed, it is entirely unnecessary at high speeds to supply additional fuel even if the temperature is low. This condition is also partly due to the fact that the temperature in the bowl at speeds of 40 miles an hour or more is likely to be much lower than that of the engine itself.

A choke cone 44 is slidably mounted on the standpipe 15 and is operable by a yoke 45 mounted on an arm 46 for the purpose of restricting or cutting off the annular passage 47 between the upper end of the standpipe 15 and the throat of the venturi 4. This arrangement is used for starting or for extreme cold weather conditions, as desired.

The operation of the device is as follows:

The carburetor being attached by means of flange 7 to an internal combustion engine, air enters the air inlet 2 and flows through port 16 in the base of the standpipe up past the nozzle and through the restriction 17 in the standpipe and into the main venturi or mixing chamber 4. Air from the inlet 2 also passes through the air chamber 3 and flows through the annular space 47 around the top of the standpipe. Fuel being supplied to the bowl and maintained at a constant level A—A, the suction caused by the operation of the engine draws fuel into the passageway 38 through the bores 36, 33, 22, and 23 into the nozzle and the accelerating well 19.

Air from the air chamber flows down through the air bleed 18 and mixes with the fuel in the nozzle and the accelerating well, passing up through the discharge outlet of the nozzle into the primary mixing chamber 48 above the restriction 17 in the standpipe. When the carburetor is operated under high temperature conditions, for instance, above 70 degrees Fahrenheit, the thermally controlled element 42 will be bent to the left to close the end of the passageway 37 so that all the fuel must pass through the passageway 38, thereby providing a mixture which is calibrated for high temperature operation. When the temperature is low, as when starting up on a cold morning, the thermally controlled element 42 is bent to the right, as shown in Figures 1 and 3 to permit additional fuel to enter the passageway and to

enrich the mixture thereby in the degree of approximately 12 percent. When the choke valve 44 is closed and the throttle slightly opened, as for starting at low temperature, the suction is built up at higher than normal for the same operating speed by the fact that the choke valve is closed preventing the relief of the suction by air entering at 47. When the engine is cranked at normal cranking speeds, say, from 40 to 100 R. P. M., the suction developed at such low speeds is not sufficient to close the valve 42 if the temperature is extremely low—for instance, zero Fahrenheit or below. However, when the engine starts to run under its own power, the suction is substantially built up due to the increase in operating speed of the engine to anywhere from 200 to 400 R. P. M. The high suction which will now be built up by the engine is communicated to the valve 42 which closes and leans out the mixture, and in this manner a member is provided for leaning out the mixture as soon as the engine starts to run under its own power. When the valve 44 is opened, the suction is again decreased, and if the temperature is low and the speed not above normal, the valve 42 will again be open in response to the lowered suction. It will be noted that the port 29 is posterior to the throttle valve when that valve is slightly open and the port is also posterior to the choke valve 44, so that the suction conveyed to the valve 42 may be responsive to movements of either the throttle or choke valve, and the claims should be construed accordingly. When the engine reaches normal operating temperature, heat from the engine is conducted down through the body to the carburetor and the extension 10 to the fuel in the bowl, thereby warming the fuel in the bowl and the thermally controlled element 42 which thereupon bends to the left and closes the end of the orifice 37.

When the fuel in the main fuel tank is very cold and the car is operated at high speed, the temperature in the bowl will again fall, due to the rapid rate of flow of the cold fuel into the bowl. This, however, will not cause the thermally controlled element 42 to open the end of the passageway 37, except under extreme cold conditions, because the suction will hold the member 42 in closed position.

I claim:

1. In a carburetor, a fuel supply device for forming a combustible mixture, temperature operated means for enriching the mixture when the temperature is low, and for leaning out the mixture when the temperature is high, said temperature enriching means being inoperative at high speeds.

2. In a suction operated spray carburetor, means for forming a mixture of fuel and air, means for adjusting said fuel supply device to deliver a lean mixture when the temperature is high, means for adjusting said device

to deliver a richer mixture when the temperature is low, said last named means being inoperative at high suction.

3. In a carburetor, a thermally operated fuel controlling device comprising a flat strip of thermostatic material in the order of .017 of an inch in thickness, said strip having sufficient resiliency and flexibility to permit its being flexed by the suction of the carburetor 10 as well as by change in temperature.

4. A thermally controlled device comprising two substantially parallel members joined by a cross member, one of said parallel members being formed of bi-metallic material and 15 being entirely flat and straight, the other of said parallel members and said cross member being formed of a material that is substantially constant in shape under changes in temperature, a retaining device having a wrench-receiving portion between the unjoined ends of said members, said wrench-receiving portion having a side-port and an end-port, said side-port being open at all 20 times and said end-port being controlled by 25 the free end of the said bi-metallic material.

5. A thermostatic controlling device for carburetors comprising a body member having a fuel passageway therein, said passageway terminating in a seat-portion, the said 30 passageway being enlarged and screw-threaded at its seat-portion, a U-shaped bracket having a perforation in one end thereof and seated on said seat-portion, a screw for holding said bracket in position, 35 said screw having a longitudinal passageway therein and a transverse passageway communicating with said longitudinal passageway, the end of said longitudinal passageway being adjacent the free end of said 40 U-shaped bracket.

6. In a carburetor, a heat-operated fuel controlling device comprising a body member having a fuel passageway therein, a seat surrounding the inlet of said fuel passageway, a 45 U-shaped bracket mounted on said seat and having a perforation therein substantially concentric with said passageway, a screw-threaded member threaded to said body member for holding said U-shaped bracket in position, said screw-threaded member having an opening adjacent to free end of said U, 50 said end of said U comprising a heat responsive element.

7. In a carburetor, means forming a mixing conduit, a throttle valve controlling the flow of mixture through said conduit, means forming a constant level fuel supply chamber, a fuel conduit leading from said fuel supply chamber and having a main outlet 55 into said mixing conduit at a point anterior to said throttle, said fuel conduit having a low-speed branch discharging at one or more ports in the wall of said mixing conduit, said port or ports being located at a point adjacent the edge of said throttle valve when it

is in closed position, said fuel conduit having an inlet located below the fuel level in said constant level fuel chamber, and a heat operated valve for controlling said inlet.

8. In a carburetor, means forming a mixing conduit, a throttle valve controlling the flow of mixture through said conduit, means forming a constant level fuel supply chamber, a fuel conduit leading from said fuel supply chamber and having a main outlet into 70 said mixture conduit at a point anterior to said throttle, said fuel conduit having a low-speed branch discharging at one or more ports in the wall of said mixing conduit, said port or ports being located at a point adjacent 75 the edge of said throttle valve when it is in closed position, said fuel conduit having an inlet located below the fuel level in said constant level fuel chamber, and a heat operated valve for controlling said inlet, said 80 heat operated valve being also operable by suction, whereby the flow of fuel to both said main outlet and said low speed branch will be varied both by heat and by suction.

9. In a carburetor, a fuel chamber, a body member extending into said fuel chamber, a jet nozzle threaded into said body member and communicating with said fuel chamber, a baffle carried by said body member adjacent the outer end of the jet nozzle, and a pivoted 90 support for said baffle, the axis of said pivot being parallel to the axis of said nozzle, whereby the baffle may be turned aside to permit ready access to said jet.

10. In a carburetor, means forming a mixing conduit, a single fuel supply source, a connection for supplying fuel from said source to said conduit, a calibrated passageway in said connection for metering the maximum quantity of fuel which it is desired to pass 100 through said conduit, said connection having means to direct fuel from the same source through a plurality of paths from said source to said calibrated passageway, and a thermally operated device for controlling the 105 passage of fuel through one of said paths.

11. In a carburetor, means forming a mixing conduit, a single fuel supply source, a connection for supplying fuel from said source to said conduit, a calibrated passageway in said connection for metering the maximum quantity of fuel which it is desired to pass through said conduit, said connection having means to direct fuel from the same source through a plurality of paths from 110 said source to said calibrated passageway, said means including a calibrated flow restricting device in one of said paths, and a thermally operated device for controlling the flow of fuel through the other of said paths. 115

12. In a carburetor, a liquid fuel flow controlling device comprising a passageway having a pair of spaced calibrated flow restricting devices, means for causing the fluid to flow first through one of said devices, and 120 125 130

then the other, and thermally operated means for admitting or preventing the admission of additional fuel to said passageway at a point between the restricting devices, where-
5 by the metering may be accomplished at either of the restricting devices.

13. In a carburetor, means forming a mixing conduit, a single fuel bowl, conducting means for supplying fuel from said bowl to 10 said conduit, a plurality of fixed orifice metering devices, and thermally operated means for causing the fuel from said single bowl to be metered at one of said orifices when the 15 temperature is high, and at another of said orifices when the temperature is low.

14. In a carburetor, means forming a mixing conduit, a fuel bowl, means for conveying fuel from said bowl to said conduit, a metering orifice of comparatively large size in said 20 conveying means, a metering orifice of smaller size between said large orifice and the fuel

bowl, said small metering orifice being adapted to deliver fuel to said large metering orifice, means for by-passing fuel around said small metering orifice to said large metering orifice, and thermally operated means for controlling said by-pass, whereby fuel may be selectively metered at either of said metering orifices.

15. In a carburetor, a fuel chamber, a body member having a part extending into said fuel chamber, a jet nozzle carried by said part and communicating with said fuel chamber, a support held in position by said nozzle, a pivotally mounted heat controlled member carried by said support and held in position 75 adjacent said nozzle thereby, said heat controlled member being adapted to be turned to one side of said nozzle on said pivot to permit ready access to said nozzle.

In testimony whereof I affix my signature. 80
